UNITED STATES PATENT OFFICE.

LOUIS N. D. WILLIAMS, OF OGONTZ, PENNSYLVANIA.

STITCH-TRANSFERRING DEVICE FOR KNITTING-MACHINES.

1,211,021.

Specification of Letters Patent.

Patented Jan. 2, 1917.

Application filed March 17, 1916. Serial No. 84,771.

To all whom it may concern:

Be it known that I, LOUIS N. D. WILLIAMS, a citizen of the United States, residing in Ogontz, Pennsylvania, have invented certain Improvements in Stitch-Transferring Devices for Knitting-Machines, of which the following is a specification.

My invention relates to mechanism for use in connection with that method of uniting the opposite halves of a knitted web which consists in first engaging stitches around the web with a set of stitch-engaging points, then doubling one-half of the web over upon the other half, and then uniting the doubled stitches around the latter half of the web, my invention having for its object the engagement of the stitch-receiving points with the stitches of the web and the removal of said points, with the web upon them, from the machine which produced it, without material arrest of the knitting operation. This object I attain in the manner hereinafter set forth, reference being had to the accompanying drawings, in which—

Figures 1, 2 and 3 are sectional views of sufficient of an ordinary circular knitting machine, provided with a web transferring device constructed in accordance with my invention, to illustrate the successive stages in the removal of the web therefrom, and Fig. 4 is a similar sectional view illustrating another form of web transferring device in accordance with my invention.

In order to prevent confusion no attempt has been made to show in the drawing the stitches in the distant portion of the knitted web, the latter being represented as a close web which hides everything behind it.

In the drawing, 1 represents the needle cylinder of the machine, 2 the needles, 3 the ring carrying the cams whereby reciprocation of said needles is effected, 4 the web holders, 5 the ring in which the web holders are mounted so as to be reciprocable radially, 6 the ring carrying the cams whereby such radial reciprocating motion is imparted to the web holders, and 7 a yarn guide movable into and out of feeding relation with the needles 2.

The machine may, as illustrated in the drawing, be one of that type in which the needle cylinder 1 and web holder guide ring 5 are rotatable and the cam ring 3 and web holder cam ring 6 are stationary, or it may be a machine of the reverse type, in which the needle cylinder 1 and web holder guide

ring 5 are stationary and the cam ring 3 and web holder actuating ring 6 are rotatable.

Within the needle cylinder 1, and free to move vertically therein, is a cylinder 8, upon the upper end of which is mounted a transfer point carrier 9 having a circular series of stitch-engaging points 10, said point carrier being, if desired, normally retained in its proper position at the upper end of the cylinder 8 by means of any suitable form of spring catch 11.

Below the cylinder 1 of the machine is fixedly supported a ring 13 having a spring bolt 14, which may be caused to engage either with a groove 15 in the lower portion of the cylinder 8 or with a groove 16 in the upper portion of the same.

During the normal operation of the machine the cylinder 8 and the point carrier 9 occupy the position shown in Fig. 1, the upper ends of the stitch-engaging points 10 being below the top of the needle cylinder and between the inwardly projecting stems of the web holders, so that said points will not interfere with the free delivery of the knitted web over said stems and down through the central opening of the point carrier. When a sufficient length of web has been knitted the cylinder 8 and point carrier 9 are raised so as to engage the points with the stitches of a course of said web, preferably with those of a course preceding that upon the needles, and at the same time the terminal course is cast off of the needles, the web holders are retracted and retained in the retracted position, so as to free them from engagement with the web, and the yarn guide is raised to non-feeding position in respect to the needles, as shown in Fig. 2, the knitting yarn being at the same time severed, if desired. The stitch engaging points with the web upon them are then lowered through the cylinder of the machine by drawing down the cylinder 8 until the latter is engaged and held by the spring bolt 14, as shown in Fig. 3, whereupon the point carrier can be released from the cylinder 8 and removed therefrom for application to a stitch doubling and looping device. As soon as the point carrier has been lowered so as to carry the points 10 below the top of the needle cylinder, the web holders may be restored to action and the yarn feeding device 7 may be restored to feeding position, as shown in Fig. 8, the

knitting operation being thus resumed without any material break in its continuity. After the point carrier has been removed from the cylinder 8 another point carrier 5 can be readily applied thereto and the cylinder and point carrier can be raised to the position shown in Fig. 1, ready for the removal of another web from the machine as soon as the knitting of such web has been completed.

In some cases, especially in connection with stationary cylinder machines, the point holder, after the points have engaged the stitches, may be permitted to descend at the same rate that the web is being produced, until said points are below the cylinder, whereupon that portion of the web which is engaged by the points may be severed from the web above it. This mode of operation is preferable when the stitch engaging points are applied to the web from above, as shown in Fig. 4, instead of from below as in Fig. 2. The point ring may be continuous or it may consist of two semi-annular segments, and in the latter case the segments may be hinged together, if desired, as shown for instance in Fig. 4, so as to permit one half of the stitch carrying points to be turned over into registry with the other half.

Although I have shown my invention as applied to a circular knitting machine and although it will usually be employed in connection with a machine of this type, its use 35 is not limited thereto.

The transfer points and the stitches of the web are, for ease of illustration, shown as of a much coarser gage than they would be in practice.

40 I claim:

1. The combination of the needle carrier of a knitting machine with a transfer point carrier removable downwardly through said needle carrier with the web upon it, and 45 means for freeing said web from the needles.

2. The combination of the needle carrier of a knitting machine with a transfer point

carrier contained within said needle carrier and removable downwardly through the same, said point carrier having its points 50 so disposed as to engage stitches of a course preceding that upon the needles, and means for freeing said terminal course from said needles.

3. The combination of the needle carrier 55 of a knitting machine, a transfer point carrier removable downwardly through said needle carrier, a raising and lowering device upon which said transfer point carrier is mounted, and means for detachably connecting said point carrier to said raising and lowering device.

4. The combination of the needle cylinder 65 of a knitting machine, a transfer point carrier removable downwardly through said needle cylinder, a raising and lowering device upon which said transfer point carrier is mounted, and means for detachably connecting said point carrier to said raising and lowering device.

5. The combination of the needle carrier 75 of a knitting machine, a transfer point ring carrier removable downwardly through said needle carrier, a raising and lowering device upon which said point ring carrier is mounted, and means for supporting said raising and lowering device in its raised position.

6. The combination of the needle carrier 80 of a knitting machine, a transfer point carrier removable downwardly through said needle carrier, a raising and lowering device upon which said point ring carrier is mounted, and means for supporting said raising and lowering device both in its raised 85 and lowered positions.

In testimony whereof, I have signed my name to this specification, in the presence of two subscribing witnesses.

LOUIS N. D. WILLIAMS,
